(57) **CLAIM**

The ornamental design for an outboard motor tiller as shown and described.

DESCRIPTION

FIG. 1 is a front perspective view of an outboard motor tiller according to our new and ornamental design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is an enlarged view of the area noted in FIG. 1.

The evenly dashed broken lines show portions of the outboard motor tiller that form no part of the claimed design. The dash-dot broken lines in FIGS. 1 and 7 illustrate the bounds for enlargement and form no part of the claimed design.
